UNITED STATES PATENT OFFICE.

HENRY WOLLHEIM, OF MILWAUKEE, WISCONSIN.

COMBINED TABLE AND BENCH.

SPECIFICATION forming part of Letters Patent No. 415,374, dated November 19, 1889.

Application filed July 8, 1889. Serial No. 316,844. (No model.)

To all whom it may concern:

Be it known that I, HENRY WOLLHEIM, of Milwaukee, in the county of Milwaukee and State of Wisconsin, have invented a new and useful Combined Table and Bench; and I do hereby declare the following to be a full, clear, and exact description of said invention, reference being had to the accompanying drawings, and to the letters or figures of reference marked thereon, which form a part of this specification.

The object of my invention is to provide a device which may be used as a table provided with a shelf, and which may be readily converted, when desired, into a bench having a supporting-back to its seat.

Figure 1 is an end view of the device as used for a table. Fig. 2 is a side view of the same device shown in Fig. 1. Fig. 3 is an end view of the device converted into a bench.

A pair of double legs A A support thereon a flat shelf or bench B, which is permanently attached to the legs A A. Brace-
25 rods C C, inserted in the legs near the feet, hold the legs in position. Above and upon the bench B a table-top D is supported by bent legs E E E, of which there are preferably three, one at each end and one central. These legs are conveniently made of bent wood, and are fastened at their ends to the under side of the table-top, the central portion having a downwardly-exposed flat edge F, adapted to rest on the shelf B. The table-
35 top D is adjustably secured to the bench B by means of brackets G G, secured to the under side of the table-top, and brackets H H, secured to the bench B, the brackets G and H, in sets, being secured together by studs and binding-nuts I I. The brackets G G are affixed, one at each end, to the under side of the table-top D, and are each provided with a curved slot K near its lower end. The brackets H H are secured rigidly, one at each end, to the bench B, and the two sets of brackets G G and H H are so located with reference to each other, when the table-top D is in position on the bench B, that one set of brackets is just inside of and partly opposite to the other set of brackets. The table-top D is secured pivotally and adjustably to the bench B by means of studs fixed in the brackets H H, which studs pass

through the slots K K in brackets G G, and on the outer ends of which studs the nuts I 55 I turn against the brackets G G. By these means the table can be made rigid in the position shown in Figs. 1 and 2 or in the position shown in Fig. 3. The slots K K are so located and curved as to permit the legs E E 60 E to rest on their flat edges F on the top of the bench B and also to permit the tilting of the table-top over to one side of the bench B in the position shown in Fig. 3, whereby the top D becomes a back for the bench B. 65

When the device is in the form shown in Figs. 1 and 2, in which it is adapted to be used as a table, the bench B can be used as a shelf, the device being thus adapted for a table and shelf while in the position shown 70 in Fig. 1, and having the double use of a bench when in the form shown in Fig. 3.

What I claim as new, and desire to secure by Letters Patent, is—

1. The combination, with a bench B, supported on legs A A, of a table-top D, legs E E, secured to the table-top and provided with a flat bottom edge resting on the bench, and brackets G G, secured to the table-top and pivoted to brackets secured to the bench, 75 substantially as described.

2. The combination, with a bench B, supported on legs, of table-top D, provided with legs E E E, having flat lower edges F F F, and brackets G G and H H, secured, respectively, to the table D and bench B, and connected adjustably together by studs fixed in the brackets H H, which studs are provided with binding-nuts I I, substantially as described. 85

3. The combination, with a bench B, of a table-top D, provided with legs that rest on the bench and support the table-top, as a table, brackets G G, secured to the table-top and provided centrally with curved slots, 95 brackets H H, secured to the bench and provided with studs which enter the slots in the brackets G G, and nuts I I, turning on the studs against the brackets G G, substantially as described.

In testimony whereof I affix my signature in presence of two witnesses.

HENRY WOLLHEIM.
